UNITED STATES PATENT OFFICE.

HARRIS B. HOLT, OF DORMONT, PENNSYLVANIA, ASSIGNOR TO ROSEDALE FOUNDRY AND MACHINE COMPANY, OF PITTSBURGH, PENNSYLVANIA, A CORPORATION OF PENNSYLVANIA.

TRAVELING GRATE.

Application filed January 19, 1924. Serial No. 687,248.

To all whom it may concern:

Be it known that I, HARRIS B. HOLT, residing at Dormont, in the county of Allegheny and State of Pennsylvania, a citizen 5 of the United States, have invented or discovered certain new and useful Improvements in Traveling Grates, of which improvements the following is a specification.

My invention relates to improvements in 10 the structure of traveling grates, and particularly to traveling grates of the endless-chain type whereon fuel is continuously supplied to the combustion chamber of a furnace and whereon the in-brought fuel is 15 within the combustion chamber continuously consumed.

I have developed my invention in application to a chain-grate of the particular form shown in Letters Patent of the United 20 States, No. 1,476,337, granted me December 4, 1923, and in that application I shall show and describe it.

The structure in which my invention is found is illustrated in the accompanying 25 drawings. Fig. I is a fragmentary view in plan from above (certain details appearing in horizontal section) of the grate structure. Fig. II is a view in vertical and longitudinal section, showing a portion of 30 the grate structure in its assembly with the roller which sustains it. Fig. III is a detail view to larger scale, showing in side elevation the component elements of the grate structure in articulation together. Fig. IV 35 is a view in vertical and transverse section, on the plane indicated by the line IV—IV, Fig. III. Fig. V is a view of the grate bar assembly in end elevation. Fig. VI is a view similar to Fig. III (though to smaller 40 scale) illustrating a modification in the structure.

The grate shown in Figs. I—V is the grate of my patent referred to above, in that it 45 consists of a belt made up of a plurality of identical links assembled in rows and in echelon formation, and articulated upon rods threaded through eyes with which the links at their opposite ends are provided. Each link is formed medially with a T-shaped 50 extension, and in the assembly these T-shaped extensions come into alignment and, extending in substantial continuity across the grate structure, form supports upon which the grate bars themselves are strung. 55 The links are indicated in the drawings by

the reference numeral 1; the rods upon which the rows of links in echelon formation are pivotally united are indicated at 2. 3 are the T-shaped extensions upon the links, and 4 are the grate-bars which are strung in 60 rows upon the transverse supports constituted by the T-shaped extensions.

So far as concerns ventilation through the assembled links, the structure is that of my 65 patent, and will be understood on considering Fig. IV of the drawings. As there seen, the grate bars are, intermediate their length, spaced apart. Terminally, however, the square ends of the grate bars when assembled present substantially continuous 70 surfaces transversely of the grate. This particularly appears in Fig. V.

My present invention is found in provision, in such a grate as I have indicated, 75 of means for catching the ashes, as the grate at its advance end rounds the sprocket wheels or pulleys which carry and propel it,—means which prevent the ashes from falling through, to foul and clog the structure, and which insure the eventual discharge of the ashes in a direction, not 80 through the structure, but from the place of lodgment outwardly and away from the structure as a whole.

Referring particularly to Fig. II of the drawings, the endless grate structure is there shown to be carried upon a roller 5, which roller is mounted on a shaft 6. At the opposite end the grate structure will be understood to be supported on and driven by 90 sprocket wheels. It will be understood that in place of the roller 5 sprocket wheels might be provided at this end of the grate also. The direction of movement is in Fig. II indicated by an arrow. And it will be 95 perceived that, whereas along the level upper course the grate-bars stand end to end in close array, with narrow intervals between, as they round the roller, spaces 100 open between the ends of the bars. Into these spaces ashes necessarily fall, and the object which I have in view is to prevent the ashes which fall into these spaces from passing through and filling and clogging the spaces between the links and beneath and between the grate bars.

I so shape the links that they are provided with surfaces which in the assembly 105 come into substantially continuous alignment across the width of the grate and form 110

bottoms for the spaces which as the grate rounds the sprocket-wheels, open between the rows of grate-bars. These spaces then between the rows of grate-bars become pockets, in which the ashes which fall are retained, and prevented from falling through. As in the further travel of the grate these pockets are inverted, they discharge their contents, but they then discharge their contents outwardly in a direction away from the grate structure.

Specifically, as shown in Figs. II and III, the ends of the grate-bars are square, and throughout the fuel-supporting reach of the grate these square ends of successive rows of grate-bars (which present substantially continuous surfaces, as noted above) stand opposite one another, and with spaces between, which may in the building of the grate be reduced to negligible width. As in operation these links round the roller 5 these spaces between the rows of bars widen to approximately V-shaped spaces, with geometric center in the axis of the articulation rods 2. The surfaces with which the links are provided and which as the links round the roller come into continuous alignment, are themselves indicated at 12. They are in their arrangement concentric with eyes through which the articulation rods 2 extend. These surfaces 12 are so placed that as the rows of links turn in rounding the roller, row relatively to row, they (the said surfaces) extend in substantial continuity across the width of the grate, and underlie and form the bottoms of the pockets which open between the rows of grate-bars. The grate bars themselves, as has been noted, are preferably so particularly shaped that the side walls of these V-shaped pockets are substantially continuous transversely of the grate.

It is good engineering practice in such an articulated structure as this, whose links are made of cast iron and which in service is subjected to wide ranges of temperature, to reduce to relatively small extent the vertical surfaces over which the adjacent links in the row abut laterally, link against link. With this consideration in mind, the eyes formed at opposite ends of the links are encircled with bosses 11 whose vertically disposed faces, as will be perceived, are relatively narrow. This structure affords normally discontinuity of link surface from side to side, across the structure. I so far depart from the practice indicated as to widen throughout a portion of its circumferential extent the vertically disposed face of the boss and so provide transverse surfaces which as the structure rounds the roller 5 extend in substantial continuity across the width of the grate.

Referring to Fig. III, and particularly to the link on the left, which here appears

in its entirety in side elevation, it will be perceived that the bosses 11 are widened and the transverse surfaces of the link are widened on the upper side of the link, on the same side that is to say with the T-shaped extension 3. These widened surfaces 12 are arranged, one on either side of the extension 3, and they lie to left and to right of vertical planes extending through the centers of pivotal turning of the links, row 75 upon row. Understanding that the left-hand ends of the links of one row are pivoted to the right-hand ends of the links of the next adjacent row, it will be perceived that throughout the level reach of grate travel 80 these surfaces 12 of adjacent rows are more or less completely out of alignment, but that as the links swing on their pivots in rounding the sprockets, these surfaces 12 of adjacent rows of interengaged links come to 85 alignment and present substantially continuous surfaces of proper extent across the width of the structure, to serve the ends described.

The assembly and its functioning are best 90 illustrated in Fig. II. As the spaces widen, the surfaces 12 of adjacent and interpivoted rows of links come into alignment and underlie the spaces and form bottoms for pockets. These pockets hold the infalling 95 ashes and prevent further descent to the space within. As the grate advances the pockets which initially were right side up turn up side down and the ashes spill from them, but in direction away from the grate 100 structure.

The modifications shown in Fig. VI lie in these features: First, the links 1^a instead of being provided with T-shaped extensions are provided with pairs of opposite convergent extensions 3^a, and the grate-bars 4^a, instead of being provided with recesses are provided with T-shaped extensions, by means of which the grate-bars are strung in rows into the grooves formed transversely 105 of the grate structure by the assembled links.

Second, the surfaces 14 are conveniently formed upon the extensions 3^a. The continuity of surfaces 14 across the grate is not brought about by relative pivotal turning of the links, row upon row. Instead these surfaces 14 are built out on one only of each pair of extensions 3^a (conveniently the posterior), and these posterior extensions are 115 widened, so that in assembly each row constitutes a substantially continuous surface 14 across the structure, just as in the form of Fig. III the extensions 3 of each row form substantially continuous supports.

Third, the surfaces 14 are not, it will be perceived, concentric with the axis of pivotal movement between rows of links, but as the structure rounds the pulley these surfaces 14 still, as in the case first described, cooperate 130

with the end walls of the next forwardly adjacent row of grate-bars to form ash-receiving pockets. And the same desired ends are gained.

5. It will be observed of the pockets which open between the grate bars both that they are approximately V-shaped, as has already been explained; and that they are closed pockets. Ashes can escape neither forwardly 10 nor rearwardly through them to the inner part of the structure. In consequence of the essentially V-shape of these pockets with flaring walls, my grate will keep itself clean under these conditions. It sometimes happens 15 that through inattention ashes which fall through the grate are allowed to accumulate beneath and to form a heap, through the top of which the moving grate keeps ploughing its way. Since the pockets which open between the grate bars in the curved portions of the pathway of the grate are flaring and substantially closed at the bottom both rearwardly and forwardly (with respect to the direction of normal advance), 20 my grate does not pick up ashes in case it has to plow through a heap and does not under such conditions become fouled.

It sometimes is necessary in making repairs upon a grate to reverse its travel. In 25 such circumstances the fact that the space is closed rearwardly is of great advantage, because under such conditions the green coal, instead of falling through to clog the structure, merely rests in a pocket, from which it 30 will either discharge itself or from which the attendant my easily remove it.

I claim as my invention:

1. In a chain-grate structure, an endless chain grate traveling in round-ended course 40 and consisting of a plurality of links arranged in transverse rows and articulated for pivotal movement row relatively to row, and grate-bars carried by the rows of links, the said grate-bars being provided with 45 square ends which when the bars are assembled upon the rows of links form substantially continuous surfaces transversely of the grate, the successive rows of grate-bars swinging one relatively to another as 50 the grate rounds the ends of its course whereby substantially V-shaped spaces are opened between successive rows of grate-bars, the said links being provided with surfaces which elsewhere out of alignment come to 55 alignment as the grate rounds the ends of its course and form continuous bottoms for the spaces which open as aforesaid between the ends of successive grate-bars.

2. In a chain-grate structure an endless 60 chain-grate advancing in round-ended course, the said grate consisting of a plurality of rows of links pivoted row to row

in echelon formation and of square-ended grate-bars borne by said links in successive rows; the rows of grate-bars standing in 65 close succession throughout a portion of the course of grate travel and separating as the grate rounds the ends of its course with substantially V-shaped spaces between, the said links being provided with anterior and posterior surfaces which as between adjacent rows stand normally out of alignment but which throughout the rounded ends of the course of grate travel stand in alignment and afford transversely of the structure a 70 bottom to the space which opens between the rows of grate-bars.

3. A chain grate composed of links having overlapping ends articulated in a succession of rows and advancing in round-ended path, the rows of links carrying a succession of grate bars between which as the structure rounds the ends of its pathway spaces open, each link being of elongate 80 form and provided adjacent its ends with 85 transverse eyes whereby articulation is effected, the said eyes being encircled by annular bosses upon the sides of the links, the said annular bosses throughout a portion of their extent being widened to the edge of 90 the link, and the widened portions of the bosses being so situated that as the chain grate rounds the end of its pathway the widened faces of said overlapping ends of 95 the links come to alignment and form continuous bottom surfaces for the spaces opened as aforesaid, between successive grate bars.

4. In a chain-grate structure, an endless chain grate traveling in round-ended course 100 and consisting of a plurality of links arranged in transverse rows and articulated for pivotal movement row relatively to row, and grate-bars carried by the rows of links, the said grate-bars being provided with 105 square ends which when the bars are assembled upon the rows of links form substantially continuous surfaces transversely of the grate, the successive rows of grate-bars swinging one relatively to another as the grate rounds the ends of its course whereby spaces are opened between successive rows of grate-bars, the said links being provided with surfaces which as the grate 110 rounds the ends of its course form bottoms for the spaces which open as aforesaid between the ends of successive grate-bars.

In testimony whereof I have hereunto set my hand.

HARRIS B. HOLT.
